DEVICES FOR CLEANING VENETIAN BLINDS

Sidney Sussman, Bronx, and Norman A. Haber and
Moe Feldman, Brooklyn, N. Y.

Application March 10, 1955, Serial No. 493,336

2 Claims. (Cl. 15—394)

This invention relates to novel means for cleaning Venetian blinds. The advantages of Venetian blinds are too well known to require enumeration. A Venetian blind, however, presents a very serious cleaning problem. The slats are numerous. Each slat has two opposite surfaces to be cleaned, and each slat is subdivided by tapes into two marginal sections and an intermediate section. The blind extends the full height of a window, so that some of the slats are difficult to reach, and this adds to the difficulty of cleaning. Furniture must be moved to permit repeated ladder settings and then replaced. The result is that even the simple dusting of a blind presents a task of a very tedious nature, and that a careful and thorough washing job is seldom undertaken.

This is unfortunate because the otherwise attractive blind accumulates dust, soot and sometimes grease. The blind sometimes gets rained upon, and when this occurs the dirt which has accumulated on the associated screen is carried onto the blind in a streaked or spotted condition. On the east, west or south side of a building the blind bakes in the sun, and while a clean blind having a good quality of enamel coating can withstand this treatment, a blind loaded with sulphurous, corroding combustion products and other solid particles from the atmosphere is caused in a short time to become dull, dingy and unsightly. Before long the blind is merely tolerated, not admired. In the usual case this condition, after being submitted to with discomfort for a time, is finally corrected by sending the blind in for an expensive complete overhauling and painting.

It is the primary purpose of the present invention to provide a device of a simple, inexpensive character capable of efficient use in dusting and/or scrubbing Venetian blinds.

To this end the device is desirably made to include a multiplicity of opposed pairs of slat cleaning jaws consisting of a multiplicity of upper surface engaging jaws affixed at intervals to one carrying member and a multiplicity of lower surface engaging jaws affixed at intervals to another carrying member. The jaws carried by the two members are arranged in alternation, being effectively paired so that the jaws of a pair may be caused lightly to grip a blind slat between them, or to press directly against one another. It is a feature that the carrying members are connected with provision for relative longitudinal movement so that all the jaw pairs can be operated simultaneously toward open position or simultaneously toward closed position. A locking means is provided for retaining a desired condition of relative adjustment.

Any suitable number of jaw pairs can be provided in a single device. The illustrative structure may be assumed to comprise ten pairs although only a part of them are actually shown. Thus, twenty surfaces may be cleaned simultaneously. The device is desirably made narrow, perhaps about an inch and a half wide. This has a number of advantages. The cost of the device is limited be-

2

cause relatively little material is utilized. The device is capable of use on even relatively narrow marginal areas, being capable of movement back and forth lengthwise of the slats without being objectionably obstructed and limited by the window frame. The narrowness of the device limits the weight, and this is a very important consideration because the device must be designed to operate upon as many slats simultaneously as is feasible without imposing undue strain upon persons of limited strength and energy. For this reason it is desirable that the device be constructed chiefly of the white metals such as aluminum and magnesium or of plastic. These materials have the additional advantage that they are corrosion-proof. The invention is not, however, limited to these named materials.

It is a feature that each jaw member is provided on one surface with a soft, porous, non-abrasive spongy material, suitable to carry water or cleaning solution to the blind slats and to be rubbed along the slats without producing abrasion. These spongy bodies can be adjusted to grip the slats very lightly between them or to receive the slats with a slight clearance when the slats are to be scrubbed. The slat engaging surfaces of the sponge strips conform to the slat surfaces of a blind in transverse contour. This may be brought about by applying flat sponge strips to jaw body members of slat conforming shape, or by employing jaw body members of non-conforming shape and suitably varying the thickness of each sponge strip.

It is a point that the spongy facing members of the jaws can be compressed against one another to effect a wringing action when desired.

In its simplest form the device may consist merely of two sets of sponge-faced jaws, two carrying members and a locking member. Such a device can be used for dusting or for scrubbing. For the latter service the jaws would be wetted with a cleaning solution, wrung out partially by pressure, adjusted on the slats of a blind and worked back and forth endwise of the slats.

It is a further feature, however, that provision may be made of means for furnishing the jaws with fresh cleaning solution while they are in place on the blind.

It is still another feature that provision may be made for applying the blowing action or the suction action of a vacuum cleaner to the blind slats. This would desirably be done with the sponge-faced jaws in a dry condition, and the scrubbing would be caused to follow, when desired, as a separate operation.

The device is desirably provided with a removable and adjustable extension handle for dealing with extra wide blinds. The handle is also a convenience in reaching somewhat higher from a given level than would otherwise be possible.

Other objects and advantages will hereinafter appear. In the drawing forming part of this specification,

Figure 1 is a view in sectional elevation, broken away intermediate its ends for compactness of illustration, and showing a practical and advantageous form of Venetian blind cleaning device which is illustrative of the invention;

Figure 2 is a vertical front view, partly in section, and broken away intermediate its ends for compactness, the view being taken on the line 2—2 of Figure 1, looking in the direction of the arrows;

Figure 3 is a horizontal sectional view taken on the line 3—3 of Figure 1 looking in the direction of the arrows;

Figure 4 is a fragmentary detail sectional view showing the two uppermost pairs of jaws in a closed condition, as all the jaws would appear during a blind washing operation, the showing being otherwise like that of Figure 1; and

Figure 5 is a perspective view of a downwardly facing jaw member.

The illustrative cleaning device shown in the drawing comprises a main carrying bar 10 and an auxiliary carrying bar 12. The bar 10 is desirably a straight flat bar having a longitudinal slot 14 formed near its lower end. The auxiliary carrying bar 12 is also desirably a straight flat bar having a threaded stud 16 rigidly affixed to it. As shown, the stud is formed with a reduced end portion which is passed through an opening 18 of the bar 12 and upset. The shank of the threaded stud 16 has a spacing washer 20 mounted upon it, and is passed through the slot 14. A nut 22 having a knurled head is threaded on the stud and serves to clamp the bar 10 against a washer 20 and the bar 12. The nut 22, in cooperation with the stud 16, constitutes a means for locking the bars 10 and 12 against relative movement when desired. The bars 10 and 12 are restrained against relative pivotal movement about the axis of the stud 16 by means presently to be described. The slot 14 is made somewhat longer than the space between the corresponding edges of adjacent slats of a fully extended Venetian blind.

The bar 12 constitutes the carrier for a series of spaced, parallel upwardly facing jaws 24. The jaws 24 are disposed at intervals substantially equal to the standard spacing of corresponding slat edges of a fully extended Venetian blind. Each jaw comprises a jaw member 26, desirably of sheet metal. The jaw member 26 includes a vertically extending portion 28, which is rigidly secured to the bar 12 in any suitable manner, as by spot welding, brazing or soldering. The jaw member 26 further includes a spacing portion 30, shown as a straight horizontal portion, and a sponge carrying portion 32 which is desirably curved as shown, or otherwise suitably shaped to conform to the transverse contour of a lower face of a Venetian blind slat. Each jaw member 26 may be caused to terminate in an outer upturned lip 33.

The portion 32 has secured to its upper surface by water soluble adhesive, or by vulcanization, a soft, spongy, porous strip of material 34, herein called for brevity a sponge strip. The sponge strip, however, is not composed, as a rule, of natural sponge but rather of a synthetic sponge material such as sponge rubber, or the so-called reinforced cellulose sponge material sold under the trade name "Nylonge." The strips may be of uniform thickness or they may be varied in thickness to secure conformity with the various slat contours.

In alternation with the upwardly facing jaws 24 which are carried by the bar 12, provision is made of downwardly facing jaws 36 which are carried by the bar 10. Each jaw 36 includes a body member 38, desirably formed of sheet metal. The jaw member 38 includes a vertical portion 40 which is secured in any suitable manner, as by spot welding, brazing or soldering to the bar 10. The jaw member 38 further includes a horizontal spacing portion 42 which is formed with a slot 44 through which the bar 12 passes with comfortable clearance. It is the ends of the slots 44 which prevent substantial pivotal movement of the bar 12 relative to the bar 10. The body member 38 still further includes a sponge carrying portion 46 which is curved as shown, or otherwise suitably shaped to conform to the transverse contour of the upper face of a Venetian blind slat. The portion 46 of the jaw 36, like the portion 32 of the jaw 24, has suitably secured to it a sponge strip as already described. The spacing of the jaws 32 is the same as that of the jaws 24. The bar 10 has rigidly affixed to it an offset carrying handle 48 which is open at the bottom.

As shown in Figure 1, the opposed pairs of upwardly facing and downwardly facing jaws are separated as widely as possible. When the jaws are thus separated the device can be conveniently inserted to embrace a series of consecutive slats of a Venetian blind correspond-

ing in number to the number of jaw pairs which the device provides. Even though the slat spacing of the particular blind may not be identical with the standard spacing for which the device is ideally designed, a considerable deviation from standard spacing can be accommodated with the jaws fully separated as shown in Figure 1, or separated to a lesser but substantial extent. The bars 10 and 12 may then be relatively moved lengthwise to bring the jaws of each pair into engagement with, or substantially into engagement with, the opposite faces of one of the embraced slats of the blind, the condition being substantially that illustrated in Figure 4. The bars may be locked by tightening of the nut 22 to maintain any selected condition. The device may now be moved back and forth by the handle along the slats to wipe the dust from the slats. This may be done with the sponge strips of the jaws in a dry condition or in a moist condition as preferred. When the entire blind has been dusted it may be scrubbed with a cleaning solution. The cleaning solution to be employed is a matter of choice.

Whether the blind is to be scrubbed or merely dusted with the sponge strips damp, the same technique may be followed. The jaws may be submerged in a supply of water or of cleaning solution with the jaws in an open condition like that illustrated in Figure 1 and may then be pressed firmly together to effect a wringing action. After that they may be applied to the blind in the manner already described and worked back and forth for dusting or scrubbing purposes. The device can be cleansed and provided with fresh cleaning liquid as often as desired.

In some instances an extension handle will prove an important convenience. The handle 48 is accordingly provided with a short rigid spur 50 which terminates in a ball 52. A knurled finger nut 54 surrounds the ball and may be detachably threaded to a bent end portion of an extension handle 56. The ball and nut afford capacity for complete rotary adjustment and for a limited universal adjustment of the extension handle relative to the fixed handle. The connection may be made a rigid one by tightening the nut 54 firmly.

The extension handle 56 may be removed by unscrewing it from the nut. The handle would be used ordinarily in enabling the user, when on a ladder, to push the device a considerable distance along a very wide blind. It is also a help in reaching somewhat higher from the floor or from any other selected level than would otherwise be possible. Because the locking means 16, 22 is located at the lower end of the device, the operator can, with the aid of the extension handle, reach slats which are out of his direct reach as much as the full height of the device.

In the embodiment shown provision is made for optionally applying a liquid supplying bulb or optionally applying a vacuum cleaner hose to the device. For this purpose the handle 48 is provided with a passage 58 which communicates at its lower end with the interior of a rigidly attached downwardly facing cup-like member 60. The member 60 includes a skirt portion 62 which is formed with a bayonet slot 64 for the reception of an anchoring side pin of a vacuum cleaner hose. The hose may be applied to cause the cleaner either to blow or to suck the dust off the blind.

The member 60 also includes a neck portion 66 which is formed with an internal tapered thread for the alternative attachment of a liquid containing bulb 68. The bulb can be kept in place during the scrubbing operation, and can be pressed to squirt fresh cleaning liquid onto the sponge strips of the jaws from time to time as desired.

The passage 58 through the handle 48 communicates with a flattened tube 70 which is affixed to the outer side of the bar 10. Discharge passages 72 are formed at appropriate intervals through the bar 10 and penetrate the tube 70, as best shown in Figures 1, 3 and 4. Slots 74 are properly provided through the bar 10 for affording the

passages 72 access to the spongy faces of the jaws 24 and 36.

We have described what we believe to be the best embodiments of our invention. We do not wish, however, to be confined to the embodiments shown, but what we desire to cover by Letters Patent is set forth in the appended claims.

We claim:

1. A Venetian blind cleaner comprising, in combination, a first jaw carrying member, a first series of corresponding facing, equally spaced slat engaging, cleaning jaws rigidly affixed to said member, a second jaw carrying member, a second series of correspondingly facing equally spaced slat engaging, cleaning jaws rigidly affixed to the second carrying member, the jaws of the first and second series being oppositely faced and equally spaced, means connecting the carrying members with capacity for relative longitudinal movement to enable the corresponding confronting jaws of the two series to be moved simultaneously away from one another or simultaneously toward one another, means for locking the first and second carrying members in fixed relation when desired, a carrying and operating handle rigidly affixed to one of the carrying members, the handle and the jaw carrying member to which it is affixed being formed with passages for cleaning liquid and the jaw carrying member having outlets adjacent the jaws when in operative, cleaning positions for directing the liquid onto the cleaning faces of the jaws, and the handle including a fitting adapted for the attachment of a liquid supplying means thereto.

2. A Venetian blind cleaner comprising, in combination, a first jaw carrying member, a first series of correspondingly facing, equally spaced slat engaging, cleaning

jaws rigidly affixed to said member, a second jaw carrying member, a second series of correspondingly facing equally spaced slat engaging, cleaning jaws rigidly affixed to the second carrying member, the jaws of the first and second series being oppositely faced and equally spaced, means connecting the carrying members with capacity for relative longitudinal movement to enable the corresponding confronting jaws of the two series to be moved simultaneously away from one another or simultaneously toward one another, means for locking the first and second carrying members in fixed relation when desired, and a carrying and operating handle rigidly affixed to one of the carrying members, the handle and the jaw carrying member to which it is affixed being formed with air passages, the carrying member having outlet-inlet passages adjacent the jaws when in operative cleaning position through which air can be sucked or blown between the jaws for removing dust from the blind, and the handle including a fitting adapted for the ready attachment and detachment of a vacuum cleaner hose.
